UNITED STATES PATENT OFFICE

HELMUT SICKEL, OF LEIPZIG, GERMANY

AMPUL-FILLING DEVICE

Application filed November 15, 1923. Serial No. 674,937.

My invention refers to the automatic filling of ampules and the like and its particular object is an automatic device which permits filling and sealing ampules designed 5 to hold preparations for the use of the medical practitioner, the filling and sealing being effected in a purely mechanical way and in a very short time whereby not only manual labor is dispensed with, but also a perfect 10 sealing is obtained so that the stability and purity of the contents of the ampules is warranted.

The new device according to this invention substantially consists of a plurality of 15 carriers connected with one another and subject to a positive motion which causes the ampules to travel from the point on which they are supplied to the carrier to an inlet tube through which a measured quantity of 20 the substance, such as a liquid, passes into the ampul stationed below the inlet tube, whereupon the filled ampul is conveyed to a sealing device and from there to the point of delivery. Preferably, means are provided 25 by which ampules, the necks of which are still closed, have the closed end of their necks severed by mechanical means before being filled. Provision is further made for melting the neck of the filled ampules by 30 means of a narrow flame to the action of which the ampul is subject while its carrier is in motion, the ampul being during this time caused to rotate about its longitudinal axis. The ampules are supplied to the carriers and withdrawn therefrom by automatic means.

In the drawings affixed to this specification and forming part thereof a device embodying my invention is illustrated diagrammatically by way of example. In the 40 drawings

Figure 1 is a front elevation and

Figure 2 a side elevation with the upper portion broken away, while

45 Figure 3 is a plan view corresponding to Fig. 2 and

Figure 4 illustrates a number of details including the burner for melting the necks.

50 Fig. 5 is a detail illustration on a larger scale showing a modification,

Fig. 6 is a section on the line 6—6 of Fig. 5,

Fig. 7 is a plan view of a device for locking the shaft about which the ampules are rotating,

55 Figs. 8 and 9 are a front elevation and an end elevation, respectively, of a device for modifying the quantity of liquid charged into the ampules.

Referring to the drawings, 1 is a magazine filled with empty ampules and having a sloping bottom. Below a slot 2 in the bottom a slide 3 is arranged which is provided with a cavity 4 adapted to hold an ampul. Slide 3 is displaced from the position shown 60 in Figure 1 in such manner that an ampul is caused to enter the cavity 4, whereupon it is moved back so that the ampul is placed in front of the opening of a funnel 5 into which it will glide, coming to rest on the stationary bottom 6 of the funnel.

65 In the lower part of the device are disposed two discs 8 forming a support capable of rotation about a vertical shaft 53 and having the ampul carriers 9 mounted thereon. These carriers have the form of tubes or sleeves standing upright on the support 8.

70 The discs 8 forming the support and carrying the sleeves 9 are rotated intermittently, so as to come to a stop three times during each rotation. After an ampul has been supplied to the sleeve 9 which happens to be nearest to the bottom 6 of funnel 5, it will be carried by the rotating discs 8 to the filling device comprising the inlet tube 10. After having been filled at this point, the further rotation of discs 8 will carry the filled ampul to the sealing device formed by a burner 11. After having been sealed 75 by melting, the ampul is carried back to its initial position in order to be lifted from the sleeve and delivered into a magazine.

80 The sleeves 9 are arranged to rotate about their axes and to be displaced axially. 85 Through each sleeve extends a spindle 12 having arranged at its upper end a little plate 13, while on the lower end of the spindle, which extends through an opening in the disc 8, a friction wheel 14 is fixed. The 90 95 100

spindle 12 can be displaced longitudinally with regard to sleeve 9 and carries a catch 15 as shown in Figs. 5 and 6 which in the lowermost position of the spindle abuts against a pin 93 located near the bottom of the sleeve whereby, on the spindle being caused to rotate, the sleeve will be carried along in its rotation.

In the position shown on the right hand side of Fig. 1 the spindle 12 has been lifted by an arm 16 of a vertically reciprocable slide 17 so that the filled ampul on the plate 13 is completely free of the sleeve below it. In this position of the spindle 12, the funnel 5 is displaced in such manner that it will push the filled ampul into an open magazine 18 containing a number of filled ampules which are stored in this magazine in order to cool down after their necks have been molten. The ampul at the right hand end of magazine 18 is thereby displaced so as to enter a channel 19 which carries it to a point where it can be removed by hand or to a mechanical packing device.

The funnel 5 has a slot 7 through which that portion of the empty ampul which projects beyond the upper edge of sleeve 9 will pass on the ampul being carried towards the filling device. On passing towards this device, the closed neck portion of the ampul is caused to pass between two cutting edges formed by prisms 66 and 67 which are fixed to resilient holders 68 and 69 and which scratch or cut the neck in such manner that, as the neck portion abuts against the arm 70, it will break off. I may, however, also provide a member resembling a hammer which throws the severed portion aside. Such a device is shown at the left of Fig. 5 where one of the sleeves 9 is shown in the position it will assume shortly after leaving the cutting prisms 66 and 67. Instead of the arm 70 as shown in Figs. 1 and 3, a hammer 87 is provided. A spring 88 tends to hold the opposite end of this hammer which is fulcrumed in a frame stay 83, against a cam disc 89 on a shaft 49 to which rotation is imparted from the drive of the machine by means which will be described below. When the ampul is opposite the hammer 87, the end of the hammer enters a recess 90 of the cam disc 89 and the hammer knocks off the neck of the ampul. Preferably, a rail 92 is arranged opposite the hammer to prevent yielding of the neck under the blow.

The fine needle-like filling tube 10 is attached to a tube 20 the upper end of which is connected with a three-waycock 23 which is also connected with a pump 22 and a container 21, thereby permitting the pump 22 to alternately communicate with the container 21 and with the filling tube 10, respectively.

For the purpose of filling an ampul, the

carrier sleeve 9 positioned underneath the tube 10 is lifted together with its spindle 12, this being effected by an arm 25 of slide 17 and by an arm 26 which acts on the ring 27 located at the lower end of the sleeve. The lifted ampul is introduced from below into a small bell-mouthed tube 24 arranged for free vertical movement on the tube 10 and suspended therefrom by chains 80 or the like, the ampul carrying the bell-mouthed tube along in its vertical movement and being centered by it relatively to the tube 10 so that the neck portion of the ampul will surround the filling tube.

The lever 28 serving for turning the three-waycock 23 is connected with the slide 17 by a rod 29 and, on the slide being lifted, the cock will be turned into a position in which it connects the pump 22 with the filling tube 10. The piston of pump 22 being moved by a lever 31 operated by a rod 30 causes a measured quantity of liquid to be sucked from the container 21, provided that cock 23 has connected this container with the pump, and after the cock has been turned into the position where the pump communicates with tube 10, the contents of the pump cylinder are forced into the ampul. The stroke of the pump piston and, in consequence thereof, the quantity of liquid introduced into the ampules can be regulated by displacing the rod 30 with regard to lever 31. To this end, the lever 31 is made with a slotted eye 31' as shown in Fig. 8. A pin 95 provided with a disc 94 at one end, and a thread 96 at the other, is inserted in an eye at the end of the rod 30 and held in the slotted eye of the lever 31 by a thumb nut 97 so that the effective length of the lever may be varied.

As the disc 8 continues its rotation, the neck of the filled ampul will be carried towards the narrow flame emerging from the burner 11 (Figures 2 and 4). When the ampul is in front of the burner, the friction wheel 14 on spindle 12 will come in operative contact with a continually revolving friction wheel 71 whereby the spindle 12 is caused to rotate and, being in its lowermost position, causes the carrier sleeve 9 to rotate also whereby a reliable sealing of the neck is secured.

The container 21 is connected with a vessel 34 by a tube 32 comprising a cock 33. The vessel 34 is enclosed in a chamber 35, the lower end of which is in communication with a flue 36 supplied from below with the hot gases rising from the burner 11. The heat of such gases is utilized for sterilizing the liquid in the vessel 34.

The liquid to be filled into the ampules is introduced into the vessel 34 which carries a funnel 38, an air filter tube 39 and a thermometer 40. When the liquid in the vessel 34 has been sterilized by the hot gases from

the flue 36 the flap 81 which is hinged at 82, is turned over into the position 81' which connects the flue 36 with a chimney 37 opening into the atmosphere and bypasses the gases from the chamber 35 and the liquid in the vessel 34 is allowed to cool. The rate of cooling may be increased by blowing cold air past the container, or any other expedient. The sterilized and cooled liquid is allowed to pass into the container 21 by opening the cock 33, an air filter tube 41 mounted on the container 21 securing its contents against contamination. Therefore the container 21 is always filled without it being necessary to replace it. The advantage of directly connecting the vessel 34 in which the liquid is sterilized with the container 21 resides in the facts that it is possible to supply liquid to the tank 21 without danger of pollution, and that it is not necessary to remove the container 21 and the charging apparatus from the device for sterilization so that the device may be operated continuously. Nor is it necessary to remove the said parts when the liquid is exchanged.

The vessel 34, the container 21 and the pipe lines are cleaned by forcing sterilized water or steam through them, with consideration of this method of cleaning, sharp bends should be avoided.

All the moving parts comprised in the device are driven by an electromotor 42 whose shaft 43 acts by means of a worm 44 on a worm gear 45 mounted on a shaft 46, the rotation of which is transmitted by means of a worm 47 and worm wheel 48 to a shaft 49 which serves for moving the disc 8, slide 3, funnel 5, pump 22 and slide 17.

On shaft 49 is mounted a disc 50 carrying on its circumference three teeth 51 which during each revolution of shaft 49 come into gear with the toothed wheel 52 fixed on shaft 53 of disc 8 and impart to disc 8 an intermittent rotation.

In order to bring shaft 53 to a stop at the stations where the ampules are supplied and delivered, filled and sealed, a ratchet disc 54 is fixed to this shaft as will best be seen in Figs. 5 and 7, this disc having notches 86, into which a ratchet lever 55 fulcrumed at 85 projects. A lug 56 is fixed to lever 55 and a cam disc 57 presses on this lug when the shaft 53 is to be released for rotation, thereby causing lever 55 to release ratchet disc 54. 84 is a pull-back spring secured to the lug 56 at one end.

Shaft 49 carries a crank arm 58 which is connected by means of rod 59 with a cross head 60 sliding on a rail 61 and serving, when abutting against the supports 62 and 63 of slide 3, to displace the slide 3 so as to supply ampules from the magazine 1 to the funnel 5. During this movement of slide 3 funnel 5 is carried along by the supports

62 and 63 abutting against the parts 64 and 65, respectively, connected with the funnel. With the support 63 of slide 3 the connecting rod 30 is connected so that the movement of slide 3 also sets the pump 22 in operation.

The crank arm 58 is connected by the rod 76 with a rod 72 capable of moving in guides formed by extensions 73 fixed to the slide 17 and embracing the standard 74 which serves as a guide for the slide 17, the extensions 73 gliding on the standard with so much friction that their downward movement is prevented. Rod 72 carries a catch 75 which, on meeting the extensions 73, displaces the slide 17.

The worm 44 mounted on shaft 43 further drives the worm wheel 77 on shaft 78 which carries the friction wheel 71 serving to cause the spindles 12 to rotate while the narrow flame is acting on the necks of the ampules.

A fan 79 driven by the motor 42 serves for supplying air to the burner 11.

The filling device proper described above can be replaced by any other filling device allowing to introduce a measured quantity of liquid into the ampules. By providing a plurality of parts such as described the device can also be arranged for simultaneously filling and sealing a plurality of ampules.

I wish it to be understood that I do not desire to be limited to the exact details of construction shown and described, for obvious modifications will occur to a person skilled in the art.

I claim:—

1. Filling device for ampules and the like comprising a support rotatable about a vertical axis, means for intermittently rotating said support, a plurality of ampul carriers arranged on said support, an inlet tube above said support for filling said ampules, a vertically movably spindle in said support below said tube, and means on said support for lifting said spindle towards said tube.

2. Filling device for ampules and the like, comprising a support rotatable about a vertical axis, means for intermittently rotating said support, a plurality of ampul carriers arranged on said support, an inlet tube above said support for filling said ampules, a spindle vertically movable in each carrier to support an ampul, and means for lifting the spindle in the carrier nearest to said tube so as to cause said tube to enter the ampul resting on said spindle.

3. Filling device for ampules and the like, comprising a support rotatable about a vertical axis, means for intermittently rotating said support, a plurality of ampul carriers arranged on said support, an inlet tube above said support for filling said ampules, a spindle vertically movable in each

carrier to support an ampul, means for lifting the spindle in the carrier nearest to said tube so as to cause said tube to enter the ampul resting on said spindle, and means for simultaneously supplying liquid to said tube.

4. Filling device for ampules and the like, comprising a support rotatable about a vertical axis, means for intermittently rotating said support, a plurality of ampul carriers arranged on said support, an inlet tube above said support for filling said ampules, a spindle vertically movable in each carrier to support an ampul, means for lifting the spindle in the carrier nearest to said tube so as to cause said tube to enter the ampul resting on said spindle, and means comprising a pump and a three-way cock for simultaneously supplying liquid for said tube.

5. Filling device for ampules and the like comprising a liquid container, a source of heat for softening the ampul necks and means for guiding the heat from said source to said liquid container for sterilizing the liquid contained therein.

6. Filling device for ampules and the like comprising means for causing a plurality of ampules to travel around a common centre, means for introducing a predetermined quantity of liquid into said ampules, means in the way of said ampules for making an incision in the necks of said ampules and separate means for severing the necks, after the incision has been made.

7. Filling device for ampules and the like comprising means for causing a plurality of ampules to travel around a common centre, means for introducing a predetermined quantity of liquid into said ampules, means in the way of said ampules comprising a pair of cutters resiliently mounted for making an incision in the necks of said ampules and separate means for severing the necks, after the incision has been made.

8. Filling device for ampules and the like comprising a plurality of ampul carriers each adapted to receive an ampul and connected with each other, an inlet tube for filling the ampules, mechanism for imparting positive movement to said carriers, means for supplying each of said carriers with an empty ampul, means for severing the necks of said ampules, means for supplying a predetermined quantity of the substance with which the ampules are to be filled, through said inlet tube into the ampul which is in alignment with said inlet tube at the time, and means for sealing said filled ampules, all said means being operatively connected with said mechanism.

9. Filling device for ampules and the like comprising a support, mechanism for imparting to said support intermittent rotation about a vertical axis, a plurality of tubular ampul carriers on said support, a

spindle extending through each of said carriers, an inlet tube for filling the ampules, means for rotating said tubular carriers about their vertical axis, means for raising each carried independently of the other carriers, means for displacing said spindles longitudinally with respect to their carriers, means for connecting each spindle with said support in the lower final position of said spindle, means for supplying each of said carriers with an empty ampul, means for severing the necks of said ampules, means for supplying a predetermined quantity of the substance with which the ampules are to be filled, through said inlet tube into the ampul which is in alignment with said inlet tube at the time, and means for sealing said filled ampules, all said means being operatively connected with said mechanism.

10. Filling device for ampules and the like comprising a plurality of ampul carriers each adapted to receive an ampul and connected with each other, an inlet tube for filling the ampules, mechanism for imparting positive movement to said carriers, a bell-mouthed tube arranged on said inlet tube above said carriers, means for supplying each of said carriers with an empty ampul, means for severing the necks of said ampules, means for supplying a predetermined quantity of the substance with which the ampules are to be filled, through said inlet tube into the ampul which is in alignment with said inlet tube at the time, and means for sealing said filled ampules, all said means being operatively connected with said mechanism.

11. Filling device for ampules and the like comprising a support, mechanism for imparting to said support intermittent rotation above a vertical axis, a plurality of tubular ampul carriers on said support, a spindle extending through each of said carriers, an inlet tube for filling the ampules, means for rotating said tubular carriers about their vertical axis, means for raising each carrier independently of the other carriers, means for displacing said spindles longitudinally with respect to their carriers, a bell-mouthed tube arranged on said inlet tube above said carriers, means for supplying each of said carriers with an empty ampul, means for severing the necks of said ampules, means for supplying a predetermined quantity of the substance with which the ampules are to be filled, through said inlet tube into the ampul which is in alignment with said inlet tube at the time, and means for sealing said filled ampules, all said means being operatively connected with said mechanism.

12. Filling device for ampules and the like comprising a support, mechanism for imparting to said support intermittent rotation about a vertical axis, a plurality of tubular

- ampul carriers on said support, a spindle extending through each of said carriers, an inlet tube for filling the ampules, means for rotating said tubular carriers about their vertical axis, means for raising each carrier independently of the other carriers, means for displacing said spindles longitudinally with respect to their carriers, a bell-mouthed tube arranged on said inlet tube above said carriers, a slide adapted to place an empty ampul on the top of each spindle when it is in its highest position, means for severing the necks of said ampules, means for supplying a predetermined quantity of the substance with which the ampules are to be filled, through said inlet tube into the ampul which is in alignment with said inlet tube at the time, and means for sealing said filled ampules, all said means being operatively connected with said mechanism. 13. Filling device for ampules and the like comprising a plurality of ampul carriers each adapted to receive an ampul and connected with each other, and inlet tube for filling the ampules, mechanism for imparting positive movement to said carriers, a bell-mouthed tube arranged on said inlet tube above said carriers adapted to slide freely on said inlet tube, means for supplying each of said carriers with an empty ampul, means for severing the necks of said ampules, means for supplying a predetermined quantity of the substance with which the ampules are to be filled, through said inlet tube into the ampul which is in alignment with said inlet tube at the time, and means for sealing said filled ampules, all said means being operatively connected with said mechanism. 14. Filling device for ampules and the like comprising a plurality of ampul carriers each adapted to receive an ampul and connected with each other, an inlet tube for filling the ampules, mechanism for imparting positive movement to said carriers, means for supplying each of said carriers with an empty ampul, means for severing the necks of said ampules, means for supplying a predetermined quantity of the substance with which the ampules are to be filled, through said inlet tube into the ampul which is in alignment with said inlet tube at the time, a liquid container arranged above and connected with said inlet tube, a supply vessel arranged above and connected with said container, all said means being operatively connected with said mechanism, a frame on which said means are carried, means on said frame for melting the open ends of the filled ampules, and a flue on said frame adapted to conduct the hot gases from said melting means to said supply vessel. 15. Filling device for ampules and the like comprising a frame, a support rotatable about a vertical axis on said frame, means for intermittently rotating said support, a plurality of ampul carriers arranged on said support, an inlet tube above said support for filling said ampules, a vertically movable spindle in said support below said tube, means on said support for lifting said spindle toward said tube, means on said frame for cutting and breaking the necks of said ampules before filling said ampules, and heating means on said frame for sealing the necks after said ampules have been filled. 16. Filling device for ampules and the like comprising a frame, a support rotatable about a vertical axis on said frame, means for intermittently rotating said support, a plurality of ampul carriers arranged on said support, an inlet tube above said support for filling said ampules, a vertically movable spindle in said support below said tube, means on said support for lifting said spindle toward said tube, means on said frame for cutting and breaking the necks of said ampules before filling said ampules, heating means on said frame for sealing the necks after said ampules have been filled, and means on said frame for ejecting the filled and sealed ampules.
- In testimony whereof I affix my signature.
HELMUT SICKEL.
